ATTORNEY

UNITED STATES PATENT OFFICE.

JOHN AUGUST WALLER, OF CHICAGO, ILLINOIS, ASSIGNOR TO EXPANDED WOOD LATH CORPORATION, OF COOK COUNTY, ILLINOIS, A CORPORATION.

EXPANDED BOARD LATH.

Specification of Letters Patent. Patented Aug. 26, 1919.

1,314,107.

Application filed August 26, 1918, Serial No. 251,406.

To all whom it may concern:

Be it known that I, JOHN A. WALLER, a citizen of the United States, residing at Chicago, in the county of Cook and State of Illinois, have invented certain new and useful Improvements in Expanded Board Lath, of which the following is a specification.

My invention relates to building construction and has particular reference to expanded wood lath. The general object of the present invention is to effect further economies in material and labor; to speed up construction; to provide an expanded lath that will readily receive and key to itself mortar and other plastic coatings; to provide a form of construction and arrangement of parts adapted to be manufactured rapidly with the aid of simple machinery that will produce the finished lath in a series of uninterrupted operations, and which shall have self-contained or integral spacers that eliminate the cost of metal strips and the like and firmly hold the strips of individual lath in their proper spaced apart relations.

With the above-named objects in view my invention consists in the novel construction, combination and arrangement of parts, all as hereinafter described in detail, illustrated in the accompanying drawing and more particularly pointed out in the appended claims.

In the drawing—

Figure 1 is a face or outside view of a section of board sawed and expanded with integral connecting ribs and spacers between the individual strips of lath.

Fig. 2 is a section of board with saw-cuts therin as it appears prior to its expansion.

Fig. 3 is substantially a section on the line 3—3 of Fig. 4. Fig. 4 is a broken away portion of Fig. 1 showing the opposite or rear side of the lath and particularly the integral braces or spacers between the strips of lath.

Fig. 5 is a transverse section of Fig. 1, substantially similar to Fig. 3 with the spacer portions omitted.

In the several views the expanded board as a whole is represented by the numeral 2. In this board are a plurality of series of saw-cuts 3 to 9 inclusive, each series overlapping the adjacent series preferably about one-third of its length. The board 2 is preferably about one-fourth of an inch in thickness, so that one foot of lumber, board measure, when moderately expanded, will yield approximately eight square feet of lathing.

The saw-cuts 3 to 9 are, as shown, made at a uniform slant in the same direction with reference to the edges of the board 2, and are arranged to form connecting ribs 10, 10 between lath strips 11, 11. In the present improvement I obviate the cost, weight, material and projections from the surface of the lath involved in providing the usual means for holding lath strips in expanded positions, by providing the integral spacers 65 specifically shown in Figs. 3 and 4. As shown in Fig. 5 the diagonal ribs 10 are thinner than the strips 11 and even with the front side, which makes the rear faces of the lath project beyond said ribs. In these rear 70 portions of the strips 11 I provide enlarged or mortar-key spaces by rabbeting the edges of the strips 11 beyond the plane of the connecting ribs, as at 17, 17 Figs. 4 and 5.

The thus narrowed rear portions of the 75 strips 11 are separately identified by the numeral 18 to distinguish them from the wider outer face portions 11, 11.

Out of these rear or key portions 18 I cut at suitable intervals sections 19 by making 80 two longitudinal cuts at right angles to each other, labeled 20 and 21, and a transverse cut 22. The thus partly released section 19 is then bent out at right angles and caused to bear against the adjacent lath 11 in which 85 I provide a recess or shallow pocket 23 into which the free end of the section 19 is inserted and held against angular movement. I make it possible to bend the section 19 without breaking off the fibers at its base, 90 by partly crushing or pulping the wood as at 24, 24 which show indentations made by such pulping. This makes the fibers at the base sufficiently free and pliable to withstand without breaking off the bending strain. In 95 Figs. 3 and 4 one lath strip is separately indicated by the numeral 11'. In this strip the spacer 19 is shown before being crushed at its base and bent out and is indicated as 19'. Its dotted lines indicate its operative 100 position at the right hand side of Figs. 3 and 4 the remaining portions of which show the spacers in full lines.

The operations of sawing, pulping, expanding and bending out the spacers 19 are 105 performed practically simultaneously by an improved machine which I have provided for that purpose. In providing the usual coating of fire proof paint applied at a high temperature and drying almost instantly, 110

the ends of the spacers 19 become firmly cemented into the recesses 23. However, the tension of the connecting ribs tending to force the strips 11 together is ordinarily sufficient to hold the spacers firmly in place. Sheathing (not shown) may, in like manner, be glued or cemented to the rear sides of the sheets of lathing by applying it to the lath immediately after the dipping or coating referred to.

I claim as my invention—

1. A wood lath that consists of a board with a plurality of series of cuts therethrough and expanded into spaced-apart strips of lath with connective ribs therebetween and spacers between said strips that are also a part of said board.

2. A wood lath which consists of a board

with a series of parallel saw cuts therein and partly cut and bent out spacer portions 20 which hold said saw cuts expanded.

3. A wood lath which consists of a board having a series of substantially identically directed saw cuts therethrough and struck-out lugs thereon, expanded and arranged in 25 a series of connected lath strips spaced apart by said lugs.

4. A wood lath which consists of an expanded board having a plurality of series of identical saw cuts therethrough and having 30 also a series of spacers struck out and projecting from one strip to another and holding said strips apart.

In testimony whereof I have hereunto subscribed my name.

JOHN AUGUST WALLER.
